UNITED STATES PATENT OFFICE.

GOTTWALT SIEBER, OF PLauen, GERMANY, ASSIGNOR TO VOGTLÄNDISCHE MASCHINEN-FABRIK, OF PLauen, GERMANY.

EMBROIDERING-MACHINE.

1,193,303.

Specification of Letters Patent.

Patented Aug. 1, 1916.

Application filed July 24, 1915. Serial No. 41,806.

To all whom it may concern:

Be it known that I, GOTTWALT SIEBER, a subject of the German Emperor, residing at Plauen, in Vogtland, in the Kingdom of Saxony, Germany, have invented certain new and useful Improvements in Embroidering-Machines, of which the following is a specification.

In order to embroider a whole or uncut piece of fabric on an embroidering machine so as to produce a continuous design, the embroidering must be done in sections. To this end, after a portion or one section of the fabric is finished, it is detached from the fabric frame and wound upon a certain roller, at the same time unwinding the fabric from another roller and bringing a fresh or blank piece of fabric into the range of the stitching or embroidering implements. At such manipulation particular care must be taken that two successive portions or sections of the design coincide at all points, both on the vertical and horizontal lines of connection, and that there be no break in the continuity of the design. It was difficult to attain this result, because the threads of the fabric which are very elastic, while the fabric is stretched on the fabric frame, become distended beyond the limit of their elasticity, so that when the fabric is subsequently relaxed, a change of position of the threads of the fabric occurs. This drawback is removed by the present invention, according to which that end of the finished section of the embroidery with which the succeeding section is to be joined, is clamped in an auxiliary frame and stretched therein by suitable means vertically and horizontally without causing destruction of the texture of the fabric and maintained in that state until the unfinished section of the embroidery fabric is substituted for the completed section and is stretched tautly in the fabric frame.

My invention will be more fully understood by reference to the accompanying drawing, in which similar reference characters denote corresponding parts, and in which—

Figure 1 is a front elevation of a fabric frame showing the end of a completed section of the embroidery fabric clamped in the auxiliary frame; Fig. 2 is a detail of the auxiliary frame and Fig. 3 is a section thereof on line A—B of Fig. 2.

The fabric frame *a*, *b*, *c*, *d*, of an embroidering machine is provided at both ends with the fabric rollers *e*, *f* on the roller *e* of which is wound the unfinished or blank fabric and on *f* the finished or embroidered fabric. The part *x* of the fabric which is to be embroidered and which extends over the tambour frame is in well known manner fastened to and stretched by longitudinal members *l* having hooks *l'* and suitably supported on the tambour frame as at *A*. When that portion or section of the fabric has been finished, an auxiliary frame is placed on the embroidered part of the fabric near the end at which it is to connect with the next portion of the embroidered design and is fixed to the longitudinal members *l* by clamps *g*² or other suitable means. The frame is composed of vertical adjustable members *g*, *g* and cross members *g'*, *g'*, the members *g*, *g* being situated near one end of the members *g'*, *g'*, so that at the opposite end an opening *g*^a is left. Now this frame is so mounted on the tambour frame that the line *y*—*y* of the finished section will extend through the opening *g*^a thereof. Before, however, the completed section of the fabric is wound onto the roller *f*, *i. e.*, while the fabric is still in a tautly stretched condition on the frame, two rails or bars *h*, *i* are fixed to the auxiliary frame in such position as to completely inclose the line of connection *y*—*y* of the embroidery.

The rails or bars *h*, *i* are provided on their sides facing the embroidery fabric with a covering *k* comprising a great number of fine wires or prongs over which the embroidery fabric is stretched by suitable means, the wires or prongs being made so as not to destroy or tear the fabric, while they fully suffice to fix the fabric rigidly to the rails *h*, *i*. Now that the connection part of the fabric was thus fixed in position, the finished part of the embroidery is unhooked from the members *l* and wound onto the roller *f*, leaving the connection part clamped in the auxiliary frame, and is fed onto the roller *f* until the auxiliary frame reaches the dotted line position at the right hand end of the tambour frame. The piece of unfinished fabric unwound from the roller *e* and now extending over the entire length of the tambour frame is then fastened to the longitudinal members *l* by hooking it thereto and uniformly and tautly stretched in the

same manner as the preceding section. Then the auxiliary frame is opened, but only partly, by removing the rail *h* which lies nearest to the stitching implements. Since 5 the fabric already is stretched over the entire length of the tambour frame, the removal of the bar *h* can be effected without detriment to the goods, for should it happen that the connection line *y*—*y* of the design after the removal of rail *h* deviates from its vertical position, the error can be 10 easily rectified by correspondingly changing the position of the second bar *i*, which together with the auxiliary frame remains on 15 the fabric during the succeeding period of embroidery operation. In this manner it is possible to have the different sections of the design connected at all points with great precision and without causing any tear of 20 the threads of the fabric.

The wires or prongs *k*' of the covering *k* may be covered up by suitable material or be themselves made of material that will not rust, so as not to stain the fabric.

25 What I claim and desire to secure by Letters Patent is:

1. In an embroidering machine, the combination with the tambour frame, of a device for fixing the position of the connection line between two successive sections of 30 an embroidery design, and comprising a frame capable of being removably suspended from the tambour frame and having de-

tachable bracing members formed each with a system of gripping means adapted to grip 35 and hold the fabric in stretched condition.

2. In an embroidering machine, the combination with the tambour frame, of a device for fixing the position of the connection line between two successive sections of an 40 embroidery design, and comprising a frame capable of being removably suspended on the tambour frame, and detachable bracing members at one end of said frame, each formed on the side facing the fabric with 45 a system of gripping means adapted to grip and hold the fabric in stretched condition.

3. In an embroidering machine, the combination with the tambour frame, of a device for fixing the position of the connection 50 line between two successive sections of an embroidery design and comprising a frame capable of being suspended from the tambour frame and adapted to be fed along with the fabric, detachable bracing members 55 at one end of said frame each formed on the side facing the fabric with gripping or holding means to secure the fabric in stretched condition.

In testimony whereof I affix my signature in presence of two witnesses.

GOTTWALT SIEBER.
